(57) **CLAIM**

The ornamental design for a mixing tip, as shown and described.

DESCRIPTION

FIG. 1 is a perspective view showing the new design for a mixing tip;

FIG. 2 is a right side view thereof;

FIG. 3 is a top view thereof;

FIG. 4 is a bottom view thereof;

FIG. 5 is a front view thereof; and,

FIG. 6 is a back view thereof.

The left side view is a mirror image of the right side view. In the drawings, the broken lines depict environmental subject matter only and form no part of the claimed designs.
